NUTATING AXIS ROTARY COMPRESSOR

David O. Manseau, Berkley, Mich.

Application February 18, 1946, Serial No. 648,331

7 Claims. (Cl. 230—139)

1

This invention relates to fluid pumps or compressors, and more particularly to an improved and simplified device having a minimum number of moving parts and designed to provide a substantially balanced structure in which inertia stresses, vibration, and noise are minimized.

The invention is designed to provide a light weight positive displacement pump capable of functioning to produce either positive fluid pressure or vacuum and wherein low operating stresses are involved. Pumps of this character are required in many industrial applications such for example as to compress gaseous refrigerant to convert it to the liquid form in refrigerators of the domestic type, to develop positive fluid pressure or vacuum for operating the brakes of vehicles, and for many other purposes.

An object of this invention is to provide an improved motor compressor unit, having a minimum number of moving parts, to provide a source of fluid pressure.

A further object of the invention is to provide a motor compressor unit having a single rotatable element which functions both as the rotor of an electric motor and as the driving element of the compressor unit.

Yet another object of the invention is to provide an improved compressor wherein the ratio of capacity to weight is a maximum.

Yet another object of the invention resides in the provision of a slotted stationary member having abutments oscillatably mounted therein and contacting a gyratory impeller member to form pump chambers for compressing fluid.

Another object of the invention is to provide a fluid compressor having a generally hemispherical impeller designed to gyrate about the geometric center of the sphere in a spherical bearing to produce an improved fluid compressor.

Another object of the invention is to provide a light weight motor compressor unit which is economical to manufacture and efficient in operation.

Further objects and advantages of the invention will be apparent from the following detailed description, considered in connection with the accompanying drawings, submitted for purposes of illustration only and not intended to define the scope of the invention, reference being had for that purpose to the subjoined claims.

In the drawings, wherein similar reference characters refer to similar parts through the several views:

Fig. 1 is a vertical sectional view of a motor compressor unit embodying the present invention;

2

Fig. 2 is an enlarged view in elevation of the movable abutment;

Fig. 3 is a sectional view taken on the line 3—3 of Fig. 1;

5 Fig. 4 is a fragmentary sectional view taken substantially on the line 4—4 of Fig. 1 but showing the impeller and valve block in elevation rather than in section;

10 Fig. 5 is a fragmentary sectional view similar to Fig. 4, but showing the impeller and valve block in section; and

Fig. 6 is a view in perspective of the movable abutment and its associated parts.

Before explaining in detail the present invention it is to be understood that the invention is not limited in its application to the details of construction and arrangement of parts illustrated in the accompanying drawings, since the invention is capable of being embodied in other forms and of being practiced or carried out in various ways. Also it is to be understood that the phraseology or terminology employed herein is for the purpose of description and not of limitation.

25 Referring now to the drawings, it will be observed that the motor compressor unit includes a base member 10 to which is secured in gastight relation as by welding a dome or shell 12, to form a reservoir for the compressed fluid, as well as to constitute an enclosure for the motor-compressor unit now to be described.

The base 10 is formed with an upwardly extending casing 14 upon which is mounted a motor housing. The motor housing comprises a lower projection 16 having horizontal flanges secured 35 to similar flanges on the casing 14 by bolts 18, a horizontal circular portion provided with vertical cylindrical flange 20 nested within the shell 12, and an axial bearing 22 forming a journal for the rotor of the electric motor, hereinafter 40 described.

The upper portion of the bore of the casing 14, and the lower portion of the bore of the projection 16, are machined to spherical contour as shown at 23 in Fig. 4, the remainder of the bore 45 in each case being cylindrical. The spherical surfaces together form a zone of a sphere, which serves as a bearing for a hemispherical impeller 24, designed to gyrate about its own geometric center 25 in a manner, and for a purpose, hereinafter more fully described.

Within the cylindrical bore of the casing 14 is seated a stationary pad or valve block 26, generally cylindrical in form, but having its upper end machined to fit snugly within the spherical zone above described, and with its upper sur-

face 28 of frusto-conical shape, the frusto-conical surface lying in the cone which is generated by the plane working surface 38 of the impeller 24 as it gyrates about its geometric center (which is also the apex of the frusto-conical surface 28), so that a radius of the working surface 38 of the impeller will at all times be in contact with the surface 28 to form one wall of a pumping chamber. The block 26 is held in position by means of dowel pins 31.

The valve block 26 is preferably formed in two symmetrical halves 26a and 26b, which are separated from each other by a slot 32. The half-blocks 26a and 26b are grooved to form a central semi-cylindrical bore in which is mounted a pin 33 having an approximately hemispherical head 35. The head 35 and the upper portion of the pin 33 are formed with a slot 37 which lies in the plane of slot 32. The head 35 is seated in a hemispherical recess in the impeller 24. An abutment 34 is mounted for rocking movement within the slots 32, 37, and is provided with a bearing aperture 38 (Fig. 2) which registers with a corresponding bearing aperture 39 in the head 35. In these bearing apertures is a bearing pin 38 which is designed to form a pivot upon which the abutment 34 oscillates in synchronism with the impeller 24, to prevent flow of fluid from one side to the other of the abutment. The respective ends of the abutment thereby constitute walls of the pumping chambers. The pin 38 is located at the geometric center 25 of the impeller 24, and the upper edge 40 of the abutment extends substantially diametrically of the sphere and is rounded to fit into a semi-cylindrical groove extending diametrically of the impeller 24, to prevent rotation of the impeller relative to the abutment, and to prevent leakage of fluid from one side to the other of the abutment, while permitting a rocking motion of the impeller upon the edge 40. The outer edges 42 of the abutment are of circular contour as viewed in elevation in Fig. 2, and are also of circular contour as viewed in cross section, to conform to the spherical bearing surface 28. In oscillating about the pin 38, the respective ends of the abutment will alternately move downwardly into the slot 32, the slot beneath the path of the abutment being occupied by spacing blocks 44 which are arranged one on each side of the pin 38.

The electric motor which drives the compressor comprises a stator 46 fixedly mounted within the cylindrical flange 20, and a rotor 48 having an impeller shaft 50 journaled in the bearing 22 in driving relation to the rotor. The shaft terminates at its lower end in a disk-shaped head 52, having a cylindrical outer surface rotatably seated within the cylindrical bore of the projection 16, which forms a journal therefor, the uppermost point of the impeller 24 being in contact with the head 52.

Projecting from the lower surface of the head 52 is a stud 54, held in place by a radial pin 56. The upper end of the stud 54 is displaced radially from the axis 58 of the shaft 50, and the stud is inclined to said axis in such manner that the axis of the stud intersects the same at the spherical center 25. The stud 54 rides in a concentric bushing 60 which is seated in the impeller 24 and abuts against the lower surface of the head 52. The axis of the stud is perpendicular to the plane surface 38 of the impeller 24.

A fluid inlet duct 62 extends through the base 18 and connects with two branches 63, 64 which communicate, through suitable couplings, with

vertical bores 66, 67 formed in the block 26. At their upper ends, bores 66 and 67 are provided with check valves 68. Beyond the check valves the bores 66, 67 terminate in ports 70, 71 in the frusto-conical surface 28 of the block 26. The ports are formed as part of the slot 32, and constitute the inlet ports to the pumping chambers. Similar ports 72, 73 form the outlet ports from the pump chambers, and lead through check valves 74, 75 and branches 71, 72 to an outlet duct 80 which terminates in the upper portion of the shell 12 above the oil level. A fluid outlet conduit 82 is mounted in the top of the shell 12, and is provided with a suitable strainer 84 to separate liquid particles or other non-gaseous matter from the fluid being compressed. If the unit is used in refrigeration mechanism to compress gaseous refrigerant and convert it to liquid, the outlet 82 will be connected to a refrigerant condenser to transmit compressed gaseous refrigerant thereto, whereas the inlet duct 62 will be connected to the header of a refrigerant evaporator to withdraw gaseous refrigerant therefrom.

The check valves 68, 74 and 75 are preferably formed of hard rubber or other similar material, and act as acoustic mufflers by permitting the gas being pumped to change its volume, any sound created by the operation of the parts being dissipated by the block 26 and the surrounding oil.

The space within the shell 12 is filled with lubricating oil to a level below that of the lower edge of stator 46. Oil may therefore flow inwardly through oil hole 86 to the upper surface of the impeller 24 whence it is distributed to the various moving parts of the compressor. The pressure in casing 12 forces the oil through the hole 86 to provide increased oiling when said pressure is high. Excess oil is pumped out through the outlet duct 80. An additional oil hole 87 admits lubricant to the upper surface of head 52, where it is picked up by spiral lubricating grooves 88 on the upper surface of head 52, whence it will be entrained in a helical groove 90 formed on the outer surface of shaft 50, and thence carried upwardly to overflow at the upper end of the bearing 22. By this means a continuous flow of lubricant from the shell 12 through the moving parts of the mechanism is maintained. A plug 92 is seated in the base 18 to allow withdrawal and replenishing of the lubricant.

With the parts in the positions shown in the drawings, the space between the impeller 24 and the conical surface 28 is divided by the abutment 34 into two pumping compartments, equal to each other in horizontal projection and cubic volume, and indicated in Fig. 3 at 94 and 95. Assuming the motor to rotate in the clockwise direction, rotation of the shaft 50 will act through stud 54 to impart motion to the impeller 24, causing it to gyrate about its geometric center 25, and causing the radial line of contact between surfaces 38 and 28 to move in the clockwise direction from a line which coincides with the left half of the slot 32 as viewed in Fig. 3, to a position displaced clockwise therefrom. In so doing, the line of contact will pass over the inlet port 70, and will divide the compartment 94 into two pumping chambers, the chamber to the left of said line being of increasing volume, while the chamber to the right of said line will be of decreasing volume. Fluid will thus be drawn into the chamber at the left of the line through inlet port 70, and will be expelled from the chamber at the right of said

line through the port 73. The compartment below slot 32 in Fig. 3 will not vary greatly in volume during this operation.

When the electric motor is energized, therefore, the head 52 will be rotated and will act through stud 54 to cause gyration of the impeller 24 about its geometric center, the angle through which the working surface 30 of the impeller gyrates being equal to twice the angle between the stud 54 and the axis 58. The surface 30 will in such gyration define a cone with its apex at the geometric center 25 of the impeller, and the surface 28 of the stationary member lies in that cone.

Operation of the compressor will therefore act to draw fluid through the inlet 62 and branch 63, bore 66 and port 70 to the chamber of increasing volume, and will force fluid out from the chamber of decreasing volume through port 73, bore 75 and branch 77 to the outlet duct 80, where it will increase the fluid pressure within the shell 12. These conditions will obtain until the radial line of contact has passed the right half of slot 32, whereupon the line will define two respectively enlarging and diminishing chambers within the compartment 95, causing fluid to be drawn in by suction through the inlet port 71 and forced out by pressure through the outlet port 72, in a manner corresponding to that above described. The check valves prevent any retrograde flow of fluid.

No upper bearing for the rotor 48 of the electric motor is needed, because the stator 46 is concentrically disposed within the flange 20, and the bearing 22 is vertically extended to give a substantial bearing area to the shaft 50.

It will be apparent that if desired another fluid pump or compressor element may be positioned at the opposite end of the shaft 50 to provide a separate fluid pressure generator operating in parallel with the generator just described; or if desired one of the compressors may be connected in series with the other to receive compressed fluid therefrom and further compress it.

The impeller 24 may be formed in any suitable manner, it being contemplated that for economy of manufacture it may be made of powdered metal compressed and sintered to provide a solid homogeneous structure. By nature of its design, the impeller is inherently balanced, both statically and dynamically.

It will be apparent that the instant device may be used either as a pump and compressor, as above described, or as a suction pump to operate below atmospheric pressures to evacuate a chamber. In such case, the connections leading to and from the compressor unit would be reversed, or the direction of operation of the pump would be reversed.

Although the invention has been described with particular reference to a specific embodiment, it may be modified within the skill of artisans in this art, and is therefore not to be considered as limited in scope except by the terminology of the following claims.

I claim:

1. A motor compressor unit comprising means forming a part-spherical chamber, a stationary member having a conical surface projecting into said chamber, a diametral abutment mounted for oscillation in a slot in said stationary member, a part-spherical impeller in said chamber having a plane surface contacting the conical surface in line contact to form with said abutment pressure and suction chambers, said abut-

ment contacting a groove in said plane surface, said slot being grooved to form inlet and outlet ports communicating with said chambers contiguous to the abutment, and an electric motor having its rotor connected to said impeller in driving relation thereto.

2. A motor compressor unit comprising a housing having a part-spherical inner surface, a hemispherical impeller mounted in said housing for gyration about its geometric center, said impeller having a plane equatorial surface which in such gyration defines a cone, a groove in said surface, a member having a conical surface coinciding with said cone and having a diametral slot, a pin in said slot having a spherical head, an abutment mounted in said pin for oscillation in said slot about said geometric center and having an edge contacting said groove to form with the impeller and said member and housing and head a compression chamber, and an inlet and an outlet for said compression chamber.

3. A motor compressor unit comprising a housing having a part spherical inner surface, a hemispherical impeller mounted in said housing for gyration about its geometric center, said impeller having a plane surface which in such gyration defines a cone, a groove in said surface, a member having a conical surface coinciding with said cone and having a diametral slot, a pin in said slot having a spherical head, an abutment mounted in said pin for oscillation in said slot about said geometric center, said abutment having a rectilinear edge contacting said groove in fluidtight relation and forming with the impeller and said member and housing and head a compression chamber, and an inlet and an outlet for said compression chamber.

4. A compressor comprising a housing having a part-spherical inner surface, a hemispherical impeller in said housing, drive means for causing said impeller to gyrate about its geometric center, said impeller having a plane surface which in such gyration defines a cone, a groove in said plane surface, a member having a conical surface coinciding with said cone and having a diametral slot, a pin in said slot having a spherical head, an abutment mounted in said pin for oscillation in said slot about an axis passing through said geometric center, said abutment having a surface in articulated contact with said groove in fluid tight relation thereto and forming with the impeller and said member and housing and head a compression chamber, and an inlet and an outlet for said compression chamber.

5. The invention defined in claim 4, comprising in addition a fluid-tight container enclosing the mechanism and forming a reservoir for lubricant and an accumulator for fluid compressed by the compressor.

6. The invention defined in claim 4, comprising in addition rotary driving means for the compressor, and means associated with said driving means for circulating lubricant in contact with the moving parts of the compressor.

7. The invention defined in claim 4, comprising in addition a fluid-tight container for said compressor, a fluid conduit leading from the exterior of said container to the compressor, and a second fluid conduit leading from the compressor to the interior of the container.

DAVID O. MANSEAU.
